UNITED STATES PATENT OFFICE.

FRED DAVENPORT, OF AVONDALE, OHIO.

DESIGN FOR A BOX.

SPECIFICATION forming part of Design No. 18,623, dated September 25, 1888.

Application filed July 31, 1888. Serial No. 281,566. Term of patent 3½ years.

To all whom it may concern:

Be it known that I, FRED DAVENPORT, a citizen of the United States, and a resident of Avondale, in the county of Hamilton and State 5 of Ohio, have invented and produced a new and original Design for Boxes, of which the following is a specification, reference being had to the accompanying drawing, forming part thereof.

10 This design has for its object to provide a novel box; and it consists in the features hereinafter described and claimed, and shown in the accompanying drawing, in which the figure is a perspective view. The box is a representation of the form of a cooking-stove with

15 a body of substantially square shape and a front plate, A, bearing the representation of the ash-pit door a, fire-door b, oven-door c, and a top plate, B, bearing pot-hole lids e. From

the rear of the body rises an elevated back 20 plate, C, bearing a shelf, f, and the representation of a stove-pipe connection, g, the shelf having an opening, h.

What I claim, and desire to secure by Letters Patent, is—

25 The design for a box having the shape representing a cooking - range, consisting of the front plate, A, bearing the ash-pit, fire and oven doors a b c, the top plate, B, bearing the pot-hole lids e, the elevated back plate, C, the 30 shelf f, and the stove-pipe connection g, substantially as shown and described.

In testimony whereof I have hereunto set my hand.

FRED DAVENPORT.
